CLAIM

The ornamental design for an amusement car, as shown and described.

DESCRIPTION

FIG. 1 is a front perspective view of an amusement car showing my new design;

FIG. 2 is a top plan view thereof;

FIG. 3 is a side elevation view thereof;

FIG. 4 is an opposite side elevation view thereof;

FIG. 5 is a front elevation view thereof; and,

FIG. 6 is a rear elevation view thereof.

The broken lines shown in FIGS. 1, and 3-6 are for illustrative purposes only and form no part of the claimed design.
